(57) **CLAIM**

The ornamental design for a coffee stirrer, as shown and described.

DESCRIPTION

FIG. 1 is a top perspective view of a coffee stirrer, showing my design.

FIG. 2 is a bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a perspective view of the coffee stirrer in an unused state; and,

FIG. 10 is another perspective view of the coffee stirrer in FIG. 9.

(Continued)

The broken lines in the drawings depict portions of the coffee stirrer that form no part of the claimed design.
